(57) **CLAIM**

The ornamental design for a beverage bottle, as shown and described.

DESCRIPTION

FIG. 1 is a front elevational view of a new design for a beverage bottle embodying the present invention;

FIG. 2 is a rear elevational view of the beverage bottle shown in FIG. 1;

FIG. 3 is a left side view of the beverage bottle shown in FIG. 1;

FIG. 4 is a right side view of the beverage bottle shown in FIG. 1;

FIG. 5 is a bottom plan view of the beverage bottle shown in FIG. 1;

FIG. 6 is a top plan view of the beverage bottle shown in FIG. 1;

FIG. 7 is a bottom perspective view of the beverage bottle shown in FIG. 1;

FIG. 8 is a top perspective view of the beverage bottle shown in FIG. 1; and,

FIG. 9 is a view illustrating an embodiment of the beverage bottle shown in FIG. 1 with a lid.

The portions of the drawings shown in broken lines form no part of the claimed design.

1 Claim, 9 Drawing Sheets
